GREETING CARD OR THE LIKE

Eugenie J. Jones, Webster Groves, Mo.

Application January 3, 1950, Serial No. 6,970

Term of patent 14 years

(Cl. D59—2)

To all whom it may concern:

Be it known that I, Eugenie J. Jones, a citizen of the United States, residing in Webster Groves, State of Missouri, have invented a new, original, and ornamental Design for Greeting Card, or the like, of which the following is a specification, reference being had to the accompanying drawing, forming a part thereof.

The figure shows a front view of a greeting card illustrating my new design, the essential features of which reside in the portions shown in full lines.

I claim:

The ornamental design for a greeting card, or the like, substantially as shown and described.

EUGENIE J. JONES.
